UNITED STATES PATENT OFFICE.

HARLIN P. UPHAM, OF GREENVILLE, NEW HAMPSHIRE.

CHAIR SEAT AND PROCESS OF MAKING SAME.

Application filed October 27, 1923. Serial No. 671,197.

My present invention relates to seats, and more particularly to an improved chair seat and the process of making same.

Heretofore in making chair seats or slip seats adapted to be permanently or removably secured in a seat or chair frame, it has been usual to provide a seat bottom and secure to one side of said seat bottom a padding by means of a covering material, such as leather, artificial leather, fabric, or the like, and this covering material was drawn over the edges of the seat board and tacked to the under side of such board. This method of manufacture was a slow, hand-work operation,—was impossible for uniform results and was expensive, requiring highly skilled labor. Further objections were that the covering material was bunched at the corners, there was constant wear on the under edges of the bottom board and within a very short time the covering material was worn through and necessitated the entire replacing of the seat. Moreover, a great deal of material was used as that portion of the covering material folded around and under the edges of the board was wasted. In the attempt to remedy the objectionable features of prior structures, it has been proposed at various times to secure the edges of the covering material to a binding strip, but such attempts have been only partially successful and in no instance of which applicant is aware has a successful commercial chair seat been produced.

In my present invention I have obviated the objectionable features of prior devices of this character and have produced a slip seat in which I am able to produce a saving of approximately thirty per cent of the covering material heretofore considered necessary and have also produced a seat in which the folded edge of the material at the top of the chair seat protrudes outward from the bottom board or base to form a finishing edge, or bead, which finishing edge or bead acts, when the seat is either permanently or removably secured in a chair frame, to prevent access of dirt or dust which, in prior structures, has rendered a chair with a slip seat unsightly. Further, my improved seat is provided with corners neatly turned, and which, in addition to presenting a pleasing

appearance to the eye, form a corner in which the covering material is firmly and solidly secured to the seat bottom. Further, the improved means for holding the edges of the covering material in position are so constructed and arranged as to eliminate the heretofore sharp cutting edge seemingly inherent in this type of fastening device.

In constructing a seat embodying my present invention, I employ an entirely new and novel process of manufacture in which the edges of the covering material are securely attached to an enclosing strip that surrounds the peripheral edge of the bottom of the seat and in which the enclosing strip is firmly secured to the peripheral edge of the seat. In practicing my improved process and in constructing the improved slip seat, I may fold over on each other the contacting ends of the enclosing strip and secure such ends together and to the peripheral edge of the bottom by either fastening nails or tacks or by displacement of a portion of the overlapping edges themselves or I may, if I so desire, butt the ends of the encircling strip and electrically weld such butting edges together. Either method of attachment is within the scope of my invention and I do not wish to be limited to any particular form thereof.

In the accompanying drawings illustrating the various steps in the process of manufacture of my improved upholstered slip seat and a mechanism by means of which the improved process of manufacturing the same may be carried out,

Fig. 1 is a plan view of a building frame in which a slip seat is positioned;

Fig. 2 is a vertical sectional elevation on the line 2—2 of Fig. 1 and showing the material forming the slip seat in position before pressure is applied;

Fig. 3 is a fragmentary vertical sectional elevation showing the same construction as in Fig. 2, but after pressure is applied to the work and before the operation of securing the encircling strip to the bottom takes place;

Fig. 4 is a view similar to Fig. 3, but after the operation of securing the encircling strip to the bottom;

Fig. 5 is a detail showing a fragment of

the encircling strip and the manner in which the same is bent to receive the edge of the covering material;

Fig. 6 is a plan view of the bottom of a completed slip seat, and

Fig. 7 is a front elevation, partly in section, showing a completed seat.

In the description of my improved slip seat, the structure thereof will be described 10 in connection with the process of making the same and in connection with one embodiment of a device by means of which such improved process may be carried out.

Referring to the drawings, 10 designates 15 a platen of a press to the top face of which is secured a hollow rectangular frame 11 provided at various points about its periphery with outwardly extending lugs 12, each of these lugs being drilled longitudinally at 20 13 and in each of these drilled portions 13 is slidably mounted a plunger 14, the inner end 15 of each of which is pointed. The inner periphery of the member 11 is provided with a ledge or seat 16 in which is adapted 25 to seat a sheet of covering material 17 and the peripheral edge of the sheet of covering material 17 is fitted into a groove 18 formed in one edge of a strip 19 of metal or other suitable material. This groove 18 is formed, 30 as clearly shown in Fig. 5, by folding such strip in a U-shaped groove 20 with the extreme edge 21 folded back on the material. The peripheral edge of the covering material 17 fits into the groove 18 and that portion 21 35 above described being rounded at the point of its engagement with the covering material 17, prevents cutting of such covering material at this point. As viewed in Fig. 2, the groove 18 is an open groove with the peripheral edge 40 of the covering material 17 fitting therein. A rectangular frame of metal or other suitable material 22 is fitted inside the upstanding edge of the enclosing strip 19 and the lower edge of this rectangular frame is made 45 thin and flexible, as shown at 23, while the upper inner faces of the rectangular frame are flared outwardly, as indicated at 24, to allow the ready insertion therein of the usual chair bottom 25. This chair bottom 25 may 50 be made of a single strip of wood or may be made of a plurality of strips of wood, as indicated in Figs. 1 and 6. Referring now to Fig. 6, it will be noted that I have shown the engaging ends of the enclosing strip 19 55 as overlapping each other at 26 and I may secure the overlapping ends by riveting, soldering, or in any other suitable manner, and and it is to be understood that I may dispense with the overlapping ends 26 and butt 60 the ends of the encircling strip 19 together and either leave the abutting ends of the encircling strip 19 secured or may butt weld or compress such ends together. Before the 65 insertion in the flared end 24 of the rectangular frame of the seat bottom 25, the proper

amount of padding 27 is placed on what is ultimately to be the under surface of the covering material 17. After the padding 27 and the bottom plate 25 are in position, as shown in Fig. 2, the pressure plate 28 of the 70 press is forced downwardly by the screw step 29 and press screw 30 in the usual and ordinary way, and simultaneously with this downward pressure, pressure is applied to the upper end of the rectangular frame 22 which is likewise pressed downwardly, as viewed in Fig. 2, and the padding 27 and covering material 17 are forced downwardly into the position shown in Fig. 3. The simultaneous 75 downward movement of the rectangular frame 22 causes the groove 18 to be closed up, firmly gripping the peripheral edge of the covering material 17. Pressure being maintained on the bottom board 25, the rectangular frame 22 is moved upwardly from the position shown in Fig. 3 to the position shown in Fig. 4 and the various plungers 14 are struck smartly with a hammer or other device whereupon the pointed ends 15 thereof puncture the encircling strip 19 and cause 80 portions 31 thereof to puncture a sufficient distance into the bottom board 25 to insure that the encircling strip 19 and all parts held thereby will be held firmly in position, as shown in Fig. 4. The pressure is now removed from the bottom board 25, the plungers 14 withdrawn to the position shown in Fig. 2 or 3, the completed seat removed from the platen 10 and the process above referred to is repeated on another seat.

The folded end 21 of the strip 19 extends laterally downward from the seat bottom 25 and with the covering material 17 thereon produces a protruding or finishing peripheral edge 32 on the completed seat which, 100 when the completed seat is placed in position, acts as a finishing edge and prevents the access and collection of dust between the seat frame and the seat itself.

The covering material being cut only 110 enough larger than the seat bottom 25 to engage in the groove 18, I am enabled to effect a saving of substantially thirty per cent of the covering material over what was necessary in prior constructions. In the finished 115 slip seat, there are no ragged protruding edges of the covering material, no tacks to pull out of the covering material and allow the same to get out of shape. While I have shown a specific device for practicing the 120 improved process of manufacturing slip seats embodying my invention, yet it is to be understood that I am not limited in the carrying out of this novel process to any particular form of device.

Having thus described my invention, what I claim as new is:

The improved process of making slip seats for chairs and the like which consists in providing a strip of sheet material of a contour 125

substantially that of the desired seat, forming a groove in one edge thereof, providing a sheet of covering material, placing the peripheral edge of said sheet of covering material within the groove of the strip, placing the desired amount of padding on said covering material, forcing a seat bottom within the strip of material and simultaneously com-

pressing the padding and closing the groove in the strip of sheet material and then securing the strip of sheet material to the edge of the seat bottom. ¹⁰

In testimony whereof, I have signed my name to this specification.

HARLIN P. UPHAM.
